UNITED STATES PATENT OFFICE

105,455

DESIGN FOR AN ASHTRAY

Darvin Charles W. Trotter, Rockford, Ill.

Application May 4, 1937, Serial No. 69,149

Term of patent 3½ years

To all whom it may concern:

Be it known that I, Darvin Charles W. Trotter, a citizen of the United States, residing at Rockford, in the county of Winnebago and State of Illinois, have invented a new, original, and ornamental Design for an Ashtray, of which the following is a specification, reference being had to the accompanying drawing, forming part thereof.

I claim:—

The ornamental design for an ashtray, as shown.

DARVIN CHARLES W. TROTTER.
